UNITED STATES PATENT OFFICE

AUGUST PETRYL, OF WESTERN SPRINGS, ILLINOIS, ASSIGNOR TO EASTMAN KODAK COMPANY, OF ROCHESTER, NEW YORK, A CORPORATION OF NEW YORK

DESIGN FOR PHOTOGRAPHIC EASEL

Application filed October 6, 1930. Serial No. 37,153. Term of patent 3½ years.

To all whom it may concern:

Be it known that I, AUGUST PETRYL, a citizen of the United States of America, residing at Western Springs, in the county of Cook and State of Illinois, have invented a new, original, and ornamental Design for Photographic Easel, of which the following is a specification, reference being had to the accompanying drawing, forming a part thereof.

Figure 1 is a front elevation showing my new design for photographic easel.

Figure 2 is a rear elevation of the photographic easel shown in Figure 1.

Figure 3 is a side elevation of the photographic easel shown in Figure 1.

I claim:

The ornamental design for a photographic easel as shown and described.

Signed at Chicago, Illinois, this 16th day of September, 1930.

AUGUST PETRYL
